UNITED STATES PATENT OFFICE.

JOHN A. STRALEY, OF TOLEDO, OHIO, ASSIGNOR OF ONE-THIRD TO OTTO BOGART, OF TOLEDO, OHIO.

RAILWAY-CROSSING.

968,282.

Specification of Letters Patent. Patented Aug. 23, 1910.

Application filed April 2, 1910. Serial No. 552,972.

To all whom it may concern:

Be it known that I, JOHN A. STRALEY, a citizen of the United States, and a resident of Toledo, in the county of Lucas and State of Ohio, have invented a certain new and useful Railway-Crossing; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to railway crossings, and has for its object the provision of simple and improved means for shifting the rail sections at the crossing of two lines to alternately and selectively open or close one line 20 and simultaneously close or open the other line, which means is easy and efficient in its operation, inexpensive in its construction and maintenance, and composed of a minimum number of parts.

25 The invention is fully described in the following specification, and a preferred embodiment of the same illustrated in the accompanying drawings, in which,—

Figure 1 is a plan of a crossing embodying the features of my invention. Fig. 2 is a section of the same on the line $x-x$ in Fig. 1. Fig. 3 is a section on the line $y-y$ in Fig. 1, and Fig. 4 is a perspective view of one of the parts of the invention.

35 Referring to the drawings, 1 designates the fixed tracks or rails running in one direction, and 2 the fixed tracks or rails of the crossing line, all of which at and adjacent the point of crossing are mounted upon a 40 suitable base frame 3, shown in the present instance as being formed of I-beams. Each rail of a track is connected between the rails of the other track by two movable rail sections 4, 4, which are supported by the frame 3 and, when in longitudinal alinement, adapted to fill the space between the rails of the crossing track.

Each rail section 4 is mounted adjacent its outer end for longitudinal sliding movements in a rail-chair or member 5, which is pivoted for horizontal rotary movements upon the frame 3, and has flanges 6 adapted to overlap the base flanges of the section to slidingly hold the section to the chair. In 55 the present instance the rail-chairs are shown

as having pivot-studs 6' working within registering sockets in the frame 3 (see Fig. 3) and as being rotatably held to the frame by fingers 7, which project from such frame and hook over the rounded edges of the 60 chairs, as indicated.

The inner ends of each set of rail sections 4 are pivotally attached at their other sides in any suitable manner to the opposite ends of a cross-arm 8 of a bar or draft member 9, 65 which projects inwardly between the inner ends of the sections. The inner end of such bar is provided with a laterally angled arm 10 having a longitudinally-extending slot 11 therein which parallels the rails of the track 70 with which it is associated. The arms 10 of the opposing bars 9, which are adapted to overlap each other, extend in opposite directions from their respective bars and their slots 11 vertically register with the like slots 75 in the arms 10 attached to the rail sections 4 of the other track.

Journalized in a frame part 3^a centrally of the several rail sections 4 is a short vertical shaft 12, which carries a cross-arm or bar 13 80 at its upper end beneath the plane of the bars or draft-members 9. Studs 14 project upwardly from the ends of the cross-arm 13 and each works within the registering slots 11 of two of the bars 9, one of which projects from a set of rail sections 4 of one track while the other projects from the set of sections of the other track toward which the arm 10 of the first bar projects, as shown. A nut 15 is shown as being threaded to the 90 outer end of each stud 14 to retain the associated bars 9 in engagement therewith.

Upon a turning of the cross-arm 13 in the proper direction, outward longitudinal movements are imparted to the bars 9 of two of the opposed sets of rail sections to move the sections of such sets into alining positions to close the associated track, and inward movements are imparted to the other bars 9 to move the opposed sets of sections 4 of the 100 other track out of alining positions, as indicated, and upon giving the arm 13 a reverse quarter turn the above action is reversed. The bars 9 are guided for true horizontal movements by fins 16 projecting downwardly therefrom and working in longitudinal slots 17 provided in the subjacent frame parts 3^a, which parallel such bars.

18 designates a horizontally-disposed lever, which is fulcrumed beneath one of the 110

slotted frame parts 3^a and is provided at one end with a segmental series of teeth 19, which mesh with a pinion 20 on the shaft 12, and at its other end with a segmental series 5 of teeth 21 in mesh with the teeth of a reciprocating rack-bar 22. This rack-bar is mounted for horizontal reciprocating movements on the inner side of a portion of the frame 3 beneath one of the sets of rail sections 4 and has one end extended without the line of the other track and provided at such end with a vertical slot 23 in which the wrist-pin 24 of a crank-arm 25 works. The crank-arm 25 is carried at the end of a rock-10 shaft 26, which is journaled in a part of the frame 3 beneath the plane of the track and in a bearing part 3^b secured to the frame 3. An operating lever 27 is carried by the shaft 26, and is secured in adjusted position by a pin 28 passing through registering apertures 20 in such lever and a plate 29 fixed to the bearing part 3^b.

30 designates stop flanges which are secured to the frame part 3 in position to overlap the outer base flanges of the rail sections 4 at their inner ends and to coact therewith to limit the outward or closing movements of such sections, thus preventing their inner ends from being thrown outwardly beyond 30 a line in longitudinal alinement with the rail of the associated track.

The operation of my invention is as follows. Supposing the track to be set as indicated in the drawings with the rail sections 35 4 of the track 2 closed to provide continuous rails for such track, such rail sections may be thrown to open position and the rail sections of the other track thrown to closed position with their respective rails 40 by simply throwing the operating lever 27 to the opposite side of the shaft 26 from that shown in the drawings thus imparting substantially a half rotation to such shaft. As the shaft 26 is rotated in this manner the 45 wrist-pin 24 carried by the crank arm 25 of such shaft works within the slot 23 in the end of the rack-bar 22 and effects a longitudinal movement of such bar to oscillate the lever 18 due to the outer tooth end of such 50 lever meshing with such rack. Upon a rocking of this lever its inner pivoted end which is in mesh with the pinion 20 on the shaft 12 imparts a quarter rotation to such pinion and shaft to cause the studs 55 14 to be moved a quarter of a revolution about such shaft and to work within the slots 11 in the inner connected ends of the respectively engaged bars 9 to draw the outwardly projected bars 9 inwardly to break 60 or open the rail sections 4 of the track 2 and at the same time to force the other set of opposed bars 9 outwardly to move the attached rail sections 4 to close the track 1 for the passage of a train thereover. As 65 the rail sections 4 are moved to open the

track such sections have slight inward sliding movements in the rail chairs or members 5 to retract the outer ends of the rail sections from the continuous rails to provide a space for the passage of the flange to 70 the car wheel.

It is thus apparent that I have provided a simple and inexpensive form of crossing, the movable rail sections of which are positively moved to alternately and selectively 75 open or close one line of the track and simultaneously close or open the other line.

I wish it understood that my invention is not limited to any specific construction or arrangement of the parts except in so far as 80 such limitations are specified in the claims.

Having thus described my invention, what I claim as new and desire to secure by Letters Patent, is,—

1. In a railway crossing, the combination 85 with the two intersecting tracks, of sets of rail sections movable to connect or disconnect the rails of the tracks, and means for swinging the inner ends of opposing sets of such sections inwardly or outwardly to respectively open or close the respective tracks. 90

2. In a railway crossing, the combination with the fixed rails of two crossing tracks, of a set of oscillatory rail sections associated with a rail of each track and movable into or 95 out of alinement with such rail, the inner ends of such sections being capable of swinging inwardly from alining position and means attached to each of such sets of sections and operative to simultaneously move 100 the opposite sets of one track into alinement and the opposite sets of the other track out of alinement.

3. A railway crossing, embodying rail sections at the point of juncture of the tracks, 105 said rail sections being bodily movable in the same direction in an oscillatory manner from their positions of alinement, and means for simultaneously moving said rail sections so that those of the other pair of tracks will 110 be out of alinement.

4. A railway crossing, embodying sets of rail sections at the point of juncture of the tracks, the rail sections of each set being oscillatingly movable in the same direction 115 to and from their positions of alinement, and means for simultaneously moving said rail sections so that those of one pair of tracks will be in alinement while those of the other pair of tracks will be out of alinement. 120

5. A railway crossing, embodying rail sections at the point of juncture of the tracks, said rail sections being in pairs for each track rail and having their inner ends movable toward or away from a common point to respectively open or close the associated tracks, and means for simultaneously moving the rail sections so that those of one pair of tracks will be in alinement while 130

those of the other pair of tracks will be out of alinement with their respective tracks.

6. A railway crossing, embodying rail sections at the points of juncture of the tracks, said rail sections being arranged in sets with the sections of each set connected at their inner ends and movable together and in the same direction toward or away from alining position, bars connected to 10 the inner ends of the sections of such sets, and means operative to move said bars to simultaneously swing the sections of one pair of tracks out of alinement and the sections of the other pair of tracks into alinement.

7. A railway crossing, embodying rail sections at the point of juncture of the tracks, said rail sections being arranged in sets of two for each track and mounted for 20 longitudinal reciprocatory and oscillatory movements, the oscillatory movements of the sections of each set being in the same direction, a bar attached to and extending inwardly from the inner ends of the sections 25 of each set, and means operative to simultaneously move the bars of opposing sets to place the sections of such sets in alinement and the bars of the other two opposing sets to place the sections of such sets 30 out of alinement.

8. A railway crossing, embodying rail sections at the point of juncture of the tracks, such sections being arranged in sets of two to connect the rails of each track and 35 the sections of each set being capable of reciprocatory and oscillatory movements, the oscillatory movements being in the same direction, bars attached to the inner ends of the sections of each set and projecting inwardly therefrom, the inner ends of such 40 bars being slotted, and means coöperating with the slotted ends of such bars and operative to simultaneously move the rail sections so that those of one pair of tracks will be in 45 alinement while those of the other pair of tracks will be out of alinement.

9. A railway crossing, embodying four sets of movable rail sections, two being associated with each crossing track and movable 50 into or out of alinement with such track, members attached to the inner ends of the sections of each set and projecting outwardly therefrom, the inner ends of such members being slotted, and means coöperating 55 with the slotted ends of such members and operative to simultaneously move the sets so that those of one pair of tracks will be in alinement while those of the other pair of tracks will be out of alinement.

60 10. A railway crossing, embodying a pair of relatively movable rail sections for each track, bars attached to and projecting inwardly from the inner ends of the sections 65 of each pair and having their inner ends slotted, an oscillatory member coöperating

with the slotted ends of such bars to reciprocate the same when the member is oscillated whereby to simultaneously move opposing pairs of sections of one track out of alinement and opposing pairs of sections 70 of the other track into alinement, and means for oscillating said member.

11. A railway crossing embodying a pair of rail sections for each track of the crossing, the sections of each pair being movable 75 into or out of alining position, slotted means attached to the inner ends of the sections of each pair, and mechanism coöperating with such slotted means and operative to simultaneously move the pairs of sections so that 80 those of one pair of tracks will be in alinement while those of the other pair of tracks will be out of alinement.

12. A railway crossing, embodying a pair of rail sections for each track of the crossing, each of said pairs of sections being mounted for oscillatory and reciprocatory movements relative to the associated track, bars attached to and extending inwardly from the inner ends of the sections of each 90 pair and having their inner ends slotted, and oscillatory means coöperating with the slotted portions of such bars and operative to reciprocate the bars to move the inner ends of opposing pairs of the rail sections 95 inwardly out of alinement and simultaneously move the inner ends of the other pairs of sections outwardly into alinement.

13. A railway crossing, embodying a pair of oscillatory rail sections for each track, 100 a bar attached to and projecting inwardly from the inner ends of the sections of each pair and having their inner ends provided with slots which parallel the associated sections when in alinement, an oscillatory 105 member having parts at opposite ends thereof, each of which parts works in the slots of two of such bars, and means for oscillating said member to actuate the attached bars to simultaneously move opposing pairs of sections into alinement with 110 their respective tracks and the remaining opposing pairs out of alinement with their respective tracks.

14. A railway crossing, embodying a pair 115 of oscillatory rail sections for each track of a crossing, bars attached to and projecting inwardly from the inner ends of the sections of each pair and having their inner ends slotted, an oscillatory member coöperating 120 with the slotted ends of such bars to simultaneously move the pairs of rail sections so that those of one pair of tracks will be in alinement while those of the other pair of tracks will be out of alinement, a pinion 125 carried by said oscillatory member, a lever having its ends provided with segmental sets of teeth one set of which meshes with said pinion, and a rack-bar meshing with the other set of teeth of such lever and mov- 130

able to impart oscillatory movements to said lever and member.

15. A railway crossing, embodying a pair of inwardly oscillating rail sections for each track of a crossing, rotary supports in which the rail sections are mounted to have reciprocatory movements, a bar attached to and projecting inwardly from the inner ends of the sections of each pair and having its inner end angled and longitudinally slotted in parallelism with the rail sections when in alinement, and means coöoperating with the slotted ends of such bars and oper-

ative to simultaneously move the pairs of sections so that those of one pair of tracks 15 will be moved into alinement while those of the other pair of tracks will be moved out of alinement.

In testimony whereof, I have hereunto signed my name to this specification in the 20 presence of two subscribing witnesses.

JOHN A. STRALEY.
